(57) **CLAIM**

The ornamental design for an arm rest, as shown and described.

DESCRIPTION

FIG. 1 is a top perspective view of an arm rest in the closed position,

FIG. 2 is a bottom perspective view of the arm rest in the closed position,

FIG. 3 is a left side elevational view of the arm rest in the closed position,

FIG. 4 is a right elevational view of the arm rest in the closed position,

FIG. 5 is a back elevational view of the arm rest in the closed position,

FIG. 6 is a front elevational view of the arm rest in the closed position,

FIG. 7 is a top plan view of the arm rest in the closed position,

FIG. 8 is a bottom plan view of the arm rest in the closed position,

FIG. 9 is a top perspective view of the arm rest in the open position,

FIG. 10 is a bottom perspective view of the arm rest in the open position,

FIG. 11 is a left side elevational view of the arm rest in the open position,

FIG. 12 is a right side elevational view of the arm rest in the open position,

FIG. 13 is a back elevational view of the arm rest in the open position,

FIG. 14 is a front elevational view of the arm rest in the open position,

(Continued)

FIG. 15 is a top plan view of the arm rest in the open position; and,
 FIG. 16 is a bottom plan view of the arm rest in the open position.

The broken lines in the figures are for the purpose of illustrating portions of the arm rest which form no part of the claimed design.
